US00D974287S

(12) **United States Design Patent** (10) **Patent No.:** **US D974,287 S**
(45) **Date of Patent:** **** Jan. 3, 2023**

(54) **SUPPLEMENTAL BATTERY FOR AN ELECTRONIC WATCH**

(71) Applicant: **T-Mobile USA, Inc.**, Bellevue, WA (US)

(72) Inventors: **Christopher Painter**, Kirkland, WA (US); **Andre Sacaguti**, Sammamish, WA (US); **Aaron Takeshi Sisneros**, Oakland, CA (US); **Maikel Faltaous**, Renton, WA (US); **Jeffrey Scott Croyle**, San Francisco, CA (US)

(73) Assignee: **T-Mobile USA, Inc.**, Bellevue, WA (US)

(**) Term: **15 Years**

(21) Appl. No.: **29/761,522**

(22) Filed: **Dec. 9, 2020**

(51) LOC (14) Cl. **13-02**

(52) U.S. Cl.

USPC **D13/103**

CLAIM

The ornamental design for a supplemental battery for an electronic watch, as shown and described.

DESCRIPTION

FIG. 1 is a top perspective view of a supplemental battery for an electronic watch;

FIG. 2 is a bottom perspective view thereof;

FIG. 3 is a front elevation view thereof;

FIG. 4 rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines shown in the drawings illustrate portions of the supplemental battery for an electronic watch, as shown and described.

1 Claim, 8 Drawing Sheets
